[57] CLAIM

The ornamental design for a wall inserted step or hand box, as shown and described.

DESCRIPTION

FIG. 1 is a front elevational view of a wall inserted step or hand box showing my new design;

FIG. 2 is a front perspective view thereof; and

FIG. 3 is a side perspective view thereof.

FIG. 4 is a side elevational view thereof.

The side opposite to that shown is a mirror image thereof, and the top, bottom and rear of the box are flat and unornamented.

FIG. 1

FIG. 2

FIG. 4

FIG. 3
